ALFRED G. LEGGE, OF BROCKTON, MASSACHUSETTS.

HIGH FORM FOR SHOES.

1,115,445.

Specification of Letters Patent.

Patented Oct. 27, 1914.

Application filed March 13, 1914. Serial No. 824,529.

To all whom it may concern:

Be it known that I, ALFRED G. LEGGE, a citizen of the United States, residing at Brockton, county of Suffolk, State of Massachusetts, have invented a certain new and useful Improvement in High Forms for Shoes, of which the following is a specification, reference being had therein to the accompanying drawings.

10 My invention has for its object a hollow shoe-form constructed of leather board which is adapted for use with high shoes or as a display form for hose alone or in connection with low shoes, tango slippers and 15 the like. Hollow leather board forms, so far as I am aware, have been made in the past only in low forms for the reason that they have not been so constructed that the leather board of which they are made could 20 be properly shaped about the ankle and lower leg portion. This is due to the fact that the toe portion of a low form consists of a single piece of material which must be crimped to shape and stretched over the in- 25 step in order to obtain the shape required. This crimping operation is performed on such a machine as is shown in U. S. Letters Patent No. 804,482 granted to me November 14, 1905. Shoe-forms constructed in this 30 manner, however, cannot be made to extend above the ankle for the reason that the material will not stretch sufficiently.

The object of my invention, therefore, is to produce a hollow sheet material form 35 which extends above the ankle and has a leg portion of any length desired. The only high shoe-forms heretofore constructed so far as known to me are solid forms which are composed of wood or the like and are, 40 therefore, relatively heavy and expensive to manufacture.

The form in which my invention is embodied is light, very inexpensive to construct and much more suitable for many 45 purposes than the old solid form.

My invention makes it possible to make a hollow high shoe-form of leather board instead of solid wood as heretofore.

My invention will be fully understood 50 from the following description taken in connection with the accompanying drawings and the novel features thereof are clearly pointed out and defined in the claims at the close of the specification.

55 Figure 1 is a plan view of one of the blanks of which my improved form is com-

posed. Fig. 2 is a view in perspective of two blanks similar to that shown in Fig. 1 said blanks being stitched along the front median line. Fig. 3 is a view in perspective of a shoe form embodying my invention. Fig. 4 is a section on line 4-4 of Fig. 3.

Having reference now to the drawings, the shoe form embodying my invention consists of a pair of blanks A each cut from a sheet of leather board. They comprise a toe portion B and a leg portion C and have a front edge D which in the finished form lies along the front median line and rear edge E respectively. The front edge D is cut to correspond in general with the contour of the front median line of the last, and this permits the blank to be given the required shape to produce the completed 70 form shown in Fig. 3, when combined with another similar blank.

The two properly tempered blanks A are superimposed and sewed firmly together along the front edge D as shown at G. The 80 blanks are then opened and folded the other way so that the free lips H between the stitching G and the edge D are on the inside. The outer surface of the blanks is thus left smooth along the line G as shown at Fig. 3, 85 the lips H being then rubbed down flat as shown in Figs. 3 and 4. The blanks are then placed on a suitable last being pulled over tightly from front to back and retained in position by tacks in the manner well 90 known to those skilled in the art. The blanks are easily pulled over to cause them to conform to the shape of the last without being first crimped for by joining the two blanks along the front line G they may be 95 each cut so that when placed on the last they closely approximate its shape and are not subjected to any undue strain while being stretched over the last.

As the form is made from two blanks, the 100 edges of which in the finished form are joined along the front and back median lines, it is possible to cut the blanks in such shape that when joined together they conform to the shape of the last without being 105 submitted to the crimping operation. This makes it possible to produce a high form which could not be made at all if it were necessary to crimp the material.

In practice, I secure the blanks to the 110 form so that the edges E overlap. After the material has been set and fixed in shape

by baking or otherwise, the surplus material is cut off along the line M partly shown in Fig. 3 from the top of the form to the heel. This causes the edges of the blanks to abut 5 along the line M. The meeting edges are then secured together and reinforced by means of a strip N to which they are made fast by rivets R. While I prefer this construction, of course, any well known method 10 of securing and reinforcing the rear portion of the form may be employed.

What I claim is:

1. A hollow shoe form having a fore part and a high ankle portion composed of two 15 portions of sheet material forming opposite sides of the shoe form and secured together at their front and rear edges and shaped to the shoe last, the said sheet material being characterized by the quality of receiving the 20 shape of the last when the sheet is tempered and drawn tight over the last and of retaining said shape when set.

2. A hollow shoe form having a fore part and a high ankle portion composed of two 25 portions of leather board forming opposite sides of the shoe form and secured together at their front and rear edges and shaped to the shoe last, the said leather board being characterized by the quality of being ca-

pable of receiving the shape of the shoe last 30 when the leather board is tempered and drawn tightly over the last and of retaining said shape when set.

3. A hollow bottomless shoe form having 35 a fore part and a high ankle portion composed of two portions of leather board forming opposite sides of the form and secured together at their front and rear edges, and permanently shaped to the ankle and fore part of the shoe last.

4. A hollow shoe form having a fore part and a high ankle portion composed of two portions of sheet material, each forming one-half of the fore part and ankle portion, 45 said two portions being united together at their front and rear edges, forming a median front vertical joint and a median rear vertical joint, the said form being permanently shaped to the ankle and fore part of the last of the shoe which it is intended to 50 fit.

In testimony whereof I affix my signature, in presence of two witnesses.

ALFRED G. LEGGE.
